UNITED STATES PATENT OFFICE.

OTTO C. TRAUTMANN, OF NEW YORK, N. Y.

ACID-CONCENTRATING CHAMBER.

Application filed April 15, 1927. Serial No. 184,066.

This invention relates to concentrating chambers and it particularly relates to such chambers in which acids may be concentrated at a temperature higher than that of the atmosphere. The object of the invention is to provide means for the concentration of acids by which the heat necessarily applied to the acid is more effectively used than heretofore.

It is another object of the invention to provide means which can be operated with a minimum of repairs as all the joints, offering a possibility for the same, are always open to inspection. With these and other objections in view I shall describe in the following a concentrating chamber as an example of how my invention can be carried into effect, and for the better understanding of the same reference is had to the accompanying drawings, in which—

20 Figure 1 is a front elevation of the whole chamber, a part of the front wall, covering the inside parts, having been broken away so as to disclose these inside parts;

25 Figure 2 is a vertical sectional view of the heating chamber on the line 2—2 of Figure 1, parts of the side walls having been broken away to disclose the arrangement of the individual concentrating chambers inside the heating chamber.

30 Figure 3 shows a unit or single individual of the concentrating chambers which are assembled in a stair-way fashion into a continuous chain or system;

35 Figure 4 is a side elevation of a modification of the chamber illustrated by Figure 3.

Fig. 5 shows an apparatus similar to that illustrated by Figure 1, but having another flue arrangement.

Figure 6 is a vertical sectional view in line 40 6—6 of Figure 5 and Figure 7 shows a part of the flue arrangement applied in the construction illustrated by Figure 5.

Like numerals denote like parts throughout the drawings.

45 To carry my invention into effect I proceed as follows:

I provide a flue or heating chamber 10 to arrange therein the continuous chain or system formed by the concentrating chambers 50 11 (Fig. 3). The flue 10 is arranged in an inclined position, for instance in an angle of 45° towards the ground, and is supported by a frame work of iron or other suitable material (not shown). The bottom 12 of the flue 55 10, the front wall 13 and the roof 14 are made of any suitable material, such as bricks, plates

of fire clay, bricks of silica, or asbestos, etc. The chambers 11 are arranged above a fire box 15 having at the top a plate 16 with wide perforations 17, and intermediate said top 60 16 and the floor 18, a baffle plate 19 is arranged slightly above the gas heating arrangement 20 and approximately equidistantly from the sidewalls 21 and 22 of the flue 10. An exit 23, provided with a damper 24 for the heating gases is provided in the roof 14. The concentrating chamber 11 applied in the construction of the complete arrangement is illustrated by Figure 3; the chamber consists of the main tube or vessel 25 having a 70 neck 26 terminating in a bell 27, the neck being perpendicularly disposed to the vessel 25 in the vertical plane of their axes, while the annex 28 to vessel 25, terminating in a perpendicularly depending spigot 29, is also 75 perpendicularly disposed towards the vessel 25, but is slightly ascending towards the spigot so as to be raised somewhat above the horizontal plane. At the highest spot of this annex a tubulus 30 with a bell 31 is arranged 80 for the escape of vapors from the chambers. As to the chambers 11 I wish to say that they may have the neck 26 and the annex 28 with the spigot 29 arranged at the opposite ends of the vessel 25.

I arrange such concentrating vessels 11, having the annex 28 alternately disposed at opposite ends, within the flue 10 in such manner that I arrange a chamber 11, preferably with its main tube in a horizontal position, 90 near the bottom of the flue 10, said chamber 11 having the annex disposed at the left side and arrange then above and parallel to it another chamber which has the annex at its right side, the spigot 29 of the same being inserted and made tight in the bell 27 of the chamber 11 at the bottom. In such alternate way I arrange then the whole chain or system of chambers 11 until a sufficient number of the same are provided in the flue 10. 95 The vessels 25 are secured within the relatively thin side walls 21 and 22 and the neck 26 with bell 27 as well as the annex 28 with spigot 29 of each of the chambers 11 are located outside of the same.

100 Pipes 32 are provided on each side of the flue 10 and are connected by branch pipes 33 with each of the bells 31 arranged at the highest spot of the annex 28. These pipes 32 can be connected with any suitable means (not shown), such as an exhauster or the like, to 110 create a partial vacuum for the purpose of

sucking off the vapors generated by the heat applied to the concentrating chamber.

A preheater 34 with a lip 35 and provided with a central admission pipe 36 is arranged close by the flue. A connection pipe 37 is disposed with its bell right below the lip 35 and connected with its spigot to the bell of the uppermost concentration chamber 11. The preheater is surrounded by heat insulating means, for instance the furnace 38 provided with a source of heat, for instance a gas burner 39; the waste gases are conducted off by the connection 40 with the chimney (not shown).

Assuming that by way of example sulfuric acid be concentrated in the chamber, the operation of the same is carried out as follows:

The acid runs in a well regulated stream from a storage vessel (not shown) through the pipe 36, provided with scallops at its lower end, into the preheater 34 and flows upwardly along its inner walls, which are heated from the outside by the gas burner 39. The acid thus preheated flows over the lip 35 into the upper concentrating chamber 11 and from there through the next following chambers below until it leaves through the spigot of the last one to go to the cooler (not shown). As each of the chambers has its annex 28 slightly raised towards the spigot, a pool of acid is formed in the vessel 25 and its annex so that the acid is exposed for some time to the heat in each concentrating chamber until it flows over in the next lower chamber. It appears from Figure 2 that each vessel 25 is spaced apart from both the upper and lower adjoining chamber for the length of the annex 28 as well as of the spigot 29 and that so an arrangement in stairway fashion is brought about which is very important as far as the effect of the heat on the vessels 25 is concerned. This arrangement forces the heating gases to play around the entire outside surface of the vessels 25 and if occasionally in the various inclinations, in which the flue is disposed, the heating gases should tend to strike more closely to the front wall 13 than is desirable, the vessels 25 can be disposed nearer the front wall 13 so as to narrow the path between the vessels 25 and said front wall 13 and to thus force the heating gases according to the law of least resistance to distribute around the bottom of the vessel 25. Owing to the great heating surface of the vessels 25 in relation to the limited quantity of acid and the stepwise travel of the acid from one pool to the next one below the evaporating effect obtained is highly satisfactory. Another factor, which helps to bring about this favorable effect is the constant removal of the vapors generated in each concentrating chamber by causing them to escape through the branch pipes 33 into the pipes 32 in which constantly a partial vacuum is maintained and further

more by lowering to some extent the boiling point of the acid to be treated.

The arrangement described above as an example of how my new invention can be carried into effect, is very suitable for the concentration of sulfuric acid to the usual concentrations established in the trade, for instance for concentrating sulfuric acid from 50° to 66° Bé.

I wish to say that the arrangement described above can be changed within a wide range, but these changes refer more to the shape of the vessel 25 and not to their arrangement in stair way fashion. The vessels 11 could also be changed to the effect that the annex 28 instead of upwardly, is downwardly disposed, and that also the neck, instead of perpendicularly, is disposed in an inclined position, such as for instance shown by Figure 4, where the neck and the annex 85 are disposed in an angle of 45° to the horizontal plane, the bell 27 of this form, however, being upwardly directed and the spigot vertically depending for the reason that oblique joints are not convenient in practical work. 90

In other words, the concentrating chambers illustrated by Figure 3 may be substituted by any double bent tube having a longitudinal main part and having, if the entrance or neck should be upwardly directed, at least the end of the spigot disposed below the horizontal plane of the lowest point aforesaid longitudinal part and on one side of and distantly apart from the vertical plane of the longitudinal axis of aforesaid part. 100

It is obvious that any form of an aperture 30, whenever it can be suitably connected, will serve the purposes of my invention. In case the annex is more or less merged in the spigot such an aperture could be suitably arranged at the highest part of the spigot, for instance near the joint with the aforesaid longitudinal part.

Aside from such changes in the form of the concentrating chambers 11 further changes 110 in the construction and arrangement of my new acid concentrating chamber are still possible by changing the form and construction of the flue in which the single chambers are exposed to the heat.

In the arrangement described above all the single concentrating chambers connected into a chain, are arranged in the same flue common to all so that they, owing to the buoyancy of the heating gases, are practically exposed 120 to almost the same temperature throughout. This arrangement answers the purpose very well where great quantities of water have to be evaporated by a simple heating effect. However, in all such evaporation problems, 125 where for the obtaining of the final product ultimately relatively small quantities of water, which adhere tenaciously to the acid, have to be evaporated at high temperature, I prefer to construct the acid concentrating 130

chamber in the manner as described by Figures 5-7.

It is evident from the Figures 5 and 6 that also this device consists of a chain of concentrating chambers 11 spacedly arranged and connected with each other in exactly the same manner as described and illustrated above by Figures 1-2. The only, but considerable difference comes in by the construction 10 of the flue. Instead of arranging the single chambers 11 all in one big, wide flue, I surround the horizontal main part 25 of the chamber 11 each individually by a hollow means for conducting the heating gases 15 around it and connect such hollow means alternately by hollow connecting members so as to form a flue consisting of a pipe arranged in zigzag fashion and being besides disposed in an inclined position.

20 In the arrangement illustrated by Figure 5 the main part or horizontally disposed tube of the lowest individual chamber 11 is enclosed in a fire-box or housing 41, spaced equidistantly from the roof and from the 25 front and rear walls of the same. Below a baffle plate 42 a source of heat, for instance the gas burner 43 is operatively arranged so as to give off the heating gases striking through the housing 41. The individual 30 chambers 11 arranged above parallel to the one in the housing 41 are for instance surrounded by a flue or muffle 44, preferably of prismatic shape and divided in a lower and upper shell 45 and 46, respectively. In the 35 headwalls the flue 44 is provided with the apertures 47 and 48 of slightly larger diameter than that of the main tube 25 to be arranged in said apertures 47 and 48 in and between the shells 45 and 46. In order to 40 connect the muffle at their alternate ends with each other, a certain aperture is provided in one of the side walls near the marginal edge of the front head wall and one in the top wall or roof near the front or rear head wall. 45 Figure 7 illustrates such a muffle and shows how for instance the second muffle, counted from below, is connected with the housing below and the muffle surrounding the third individual chamber 11.

50 The housing 41 is provided with an exit 49 corresponding in size and shape to the inlet 50 of the muffle 44. The size of this aperture, corresponding in shape to the cross-section of the muffle, is slightly larger than this cross- 55 section and tapers slightly inwardly. An aperture 51 of the same size and shape is provided in the top or roof of the muffle 44 near the head wall. 52 denotes a tubular connection member having the rims of its ends 60 slightly tapering so as to fit snugly into such apertures as 49, 50 and 51. Such a connection member 52 connects the housing 41 with the muffle above by joining apertures 49 and 50, and another joins the aperture 51 with 65 the corresponding aperture 50 in the next

upper muffle 53 which is exactly the same except that its aperture is located close to the rear head wall and that its aperture 51 is located near the front head wall, wherefrom it is obvious that the spaced relation of these 70 apertures 50 and 51 alternately changes in the same manner. This arrangement described above and illustrated by Figures 5-7 is particularly effective in the concentration of sulfuric acid where it is necessary to deprive already highly concentrated sulfuric acid of its last traces of water for it is obvious that the highest concentrated acid is supplied with the greatest heat and that the temperature of the heating gases decreases upwardly in the proportion as the content of water increases in the acid to finally have the lowest heat applied to the weakest acid, therefore getting at any time and at any spot of the concentrating system a rational evaporation, both the acid and the heat passing each other in counter current principle. 80

85 The device described above and illustrated by Figures 5-7 can be joined to the preheater 34 in the same way as the device described above and illustrated by Figures 1-4. However, inasmuch as in the arrangement illustrated by Figure 5 the heat can be better utilized and escapes at its upper end 54 with considerably lower temperature, consequently with reduced buoyancy, the arrangement described above and illustrated by Figures 1-4 can be used as a preheater, substituting preheater 34 because the gases of less buoyancy will be well utilized in a big wide flue 90 as 10. There may, however, be occasions where an arrangement vice versa will be advisable. The regulating or throttling valve in the exit 54 for the heating gases are the same as those in Fig. 1. Finally I wish to say 95 that the preheater 34 may have any suitable form and that the longitudinal part of the concentrating chamber may be given any convenient shape; likewise the preheater as well as the concentrating chamber may be of the 100 same or of different material, for instance besides any acid resisting metal of fire clay, porcelain, and especially of fused silica, of which I preferably make both the preheater and the single concentrating chambers. 105 Many changes arising from the varying shape of the single concentrating chambers and adapting the principle of applying those chambers to the local needs are left to the 110 chemical engineer. 115

120 What I claim is:

1. In an acid concentrating chamber having a fire box with a source of heat and an exit for the heating gases, provided with regulating means, the combination comprising 125 an inclined flue, connecting said fire box and exit, a plurality of concentrating chambers, having horizontally extending tubular parts joined and arranged in stair-way fashion and having only said horizontal parts 130

arranged in said flue so as to have the joints located outside of the same, means for pre-heating the acid, means connecting aforesaid preheating arrangement with the uppermost concentrating chamber, and an aperture in each concentrating chamber for the escape of the vapors.

2. In an acid concentrating chamber having a fire box with a source of heat and an exit for the heating gases, provided with regulating means, the combination comprising a plurality of concentrating chambers, having horizontally extending tubular parts joined and arranged in stair-way fashion, a flue, connecting said fire box and exit, having the horizontally extending parts only of said chambers arranged therein, and means for removing the vapor from each individual concentrating chamber.

29 3. In an acid concentrating chamber having a fire box with a source of heat and an exit for the heating gases provided with regulating means, the combination comprising a plurality of concentrating chambers, having horizontally extending tubular parts joined and arranged in stair-way fashion, hollow means surrounding individually each of aforesaid horizontally disposed parts and being spaced away from the same, hollow connecting members communicatively connecting the aforesaid hollow means at alternately located ends with each other and with aforesaid fire-box and with the exit for the gases so as to form a continuous flue, means for preheating the acid, means connecting said preheating arrangement with the uppermost concentrating chamber, and an aperture in each concentration chamber for the escape of the vapors.

40 4. In an acid concentrating chamber having a fire box with a source of heat and an exit for the heating gases, provided with regulating means, the combination comprising a plurality of concentrating chambers, having horizontally extending tubular parts joined and arranged in stair-way fashion, hollow means surrounding individually each of aforesaid horizontally disposed parts only and being spaced away from the same, hollow connecting members communicatively connecting the aforesaid hollow means at alternately located ends with each other and with the aforesaid fire-box and with the exit for the gases so as to form a continuous flue.

55 5. In an acid concentrating chamber an individual concentrating chamber consisting substantially of a double bent tube having a longitudinal part, the exit of which is disposed below the entrance sidewardly on a diagonally opposite side of the longitudinal part.

60 6. In an acid concentrating chamber a concentrating chamber consisting substantially of a double bent tube having a longitudinal part and having its entrance in the form of

a neck terminating into a bell and its exit in the form of a spigot, adapted to be made tight in a bell of a neck disposed below on diagonally opposite sides of and sidewardly distantly apart from the longitudinal part. 70

7. In an acid concentrating chamber an individual concentrating chamber consisting substantially of a double bent tube having a longitudinal part and having its entrance in the form of a neck, terminating into a bell, axially disposed in the vertical plane of the longitudinal axis of its longitudinal part, and its exit in the form of a spigot, adapted to be made tight in a bell of a neck, sidewardly disposed below the horizontal part. 75

8. In an acid concentrating chamber an individual concentrating chamber consisting substantially of a double bent tube having a longitudinal part and having its entrance in the form of a neck, terminating into a bell, axially disposed in the vertical plane of the longitudinal axis of its longitudinal part and its exit in the form of an annex terminating into a spigot depending therefrom, the end of the spigot being disposed below the horizontal plane of the lowest point of said longitudinal part and on one side of and distantly apart from aforesaid vertical plane. 80

9. In an acid concentrating chamber an individual concentrating chamber consisting substantially of a double bent tube having a longitudinal part and having its entrance in the form of a neck, terminating into a bell, axially disposed in the vertical plane of the longitudinal axis of its longitudinal part and its exit in the form of an annex terminating into and ascending towards the spigot depending therefrom, the end of the spigot being disposed below the horizontal plane of the lowest point of said longitudinal part and on one side of and distantly apart from aforesaid vertical plane. 95

10. In an acid concentrating chamber, a concentrating chamber consisting substantially of a double bent tube having a longitudinal part, the exit of which is disposed below the entrance sidewardly on a diagonally opposite side of the longitudinal part and has an aperture at its joint to said longitudinal part. 110

11. In an acid concentrating chamber an individual concentrating chamber consisting substantially of a double bent tube having a longitudinal part and having its entrance in the form of a neck terminating into a bell and its exit in the form of a spigot, adapted to be made tight in a bell of a neck disposed on diagonally opposite sides of and sidewardly distantly apart from the longitudinal part. 115

12. In an acid concentrating chamber an individual concentrating chamber consisting substantially of a double bent tube having a longitudinal part and having its entrance in the form of a neck, terminating into a bell, axially disposed in the vertical plane of the 120

longitudinal axis of its longitudinal part and its exit in the form of a spigot, adapted to be made tight in a bell of a neck, disposed below the horizontal plane of the lowest point of 5 said horizontal part and on one side of and distantly apart from aforesaid vertical plane, and having an aperture at the highest point of its spigot.

13. In an acid concentrating chamber an 10 individual concentrating chamber, consisting substantially of a double bent tube having a longitudinal part and having its entrance in the form of a neck, terminating into a bell, axially disposed in the vertical plane 15 of the longitudinal axis of the longitudinal part and its exit in the form of an annex terminating into a spigot depending therefrom, the end of the spigot being disposed below the horizontal plane of the lowest point of 20 said longitudinal part and on one side of and distantly apart from aforesaid vertical plane,

and having an aperture at the highest point of its annex.

14. In an acid concentrating chamber an 25 individual concentrating chamber consisting substantially of a double bent tube having a longitudinal part and having its entrance in the form of a neck, terminating into a bell, axially disposed in the vertical plane of the longitudinal axis of its longitudinal part and 30 its exit in the form of an annex terminating into and ascending towards a spigot depending therefrom, the end of the spigot being disposed below the horizontal plane of the lowest point of said longitudinal part and 35 on one side of and distantly apart from aforesaid vertical plane, and having an aperture at the highest point of its annex.

In witness whereof I have hereunto set my name and signature this 14th day of April, 1927.

OTTO C. TRAUTMANN.
